Term of patent 14 years

(Cl. D74—5)

FIG. 2

FIG. 3

FIG. 1

FIG. 4

FIG. 5

Fig. 1 is a front elevational view of a desk calendar, showing my new design;

Fig. 2 is a top plan view of the calendar shown in Fig. 1;

Fig. 3 is a side elevational view thereof;

Fig. 4 is a side elevational view thereof showing the side opposite to that of Fig. 3 as it appears with the easel in extended position; and

Fig. 5 is a rear elevational view thereof.

The essential features of my design reside in the portions shown in solid lines on the drawing.

I claim:

The ornamental design for a desk calendar, substantially as shown and described.
